(57) **CLAIM**

The ornamental design for a wand mounted light for vacuum cleaner, as shown and described.

DESCRIPTION

FIG. 1 is a perspective view of a wand mounted light for vacuum cleaner showing my new design;

FIG. 2 is a front elevational view thereof;

FIG. 3 is a right side elevational view, the left side being a mirror image thereof;

FIG. 4 is a rear elevational view thereof; and,

FIG. 5 is a top plan view thereof.

The details shown in broken lines are for illustrative purposes only and form no part of the claimed design.
